CLAIM

The ornamental design for a tool handle, as shown and described.

DESCRIPTION

FIG. 1 is a perspective view of a the tool handle showing my new design;

FIG. 2 is a front view of the tool handle of FIG. 1;

FIG. 3 is a side view of the tool handle of FIG. 1;

FIG. 4 is a top view of the tool handle of FIG. 1;

FIG. 5 is a bottom view of the tool handle of FIG. 1; and,

FIG. 6 is a back view of the tool handle of FIG. 1.

The broken line showing of portions of the tool handle is included for the purpose of illustrating environmental structure and forms no part of the claimed design.
